UNITED STATES PATENT OFFICE

WILLIAM H. SOMMER, OF PEORIA, ILLINOIS

DIE STRUCTURE

Application filed November 15, 1928. Serial No. 319,603.

This invention has reference to new and useful improvements in die-structures and to such as are useful in wire fence machines for clenching staple-ties about the intersections of strand wires and crossed stay wires when manufacturing wire fences or fence fabrics.

The type of wire fence machines and die-structures to which the present invention applies, is best illustrated in the patent to my brother, J. W. Sommer, deceased, No. 1,078,702, dated November 18, 1913, and to the die-structure best seen on Sheets 8 and 9 of the drawings of said patent.

It has been a common practice, so far as I am aware, and it was common practice at the date of the foregoing patent to crimp the longitudinal strand or line wires at the intersections of the strand and stay wires and at or near the point of application of the staple tie wires; but for a long time difficulties have been experienced in manufactured wire fencing to stretch the same taut, while at the same time have it remain erect 25 without flexing or bowing vertically, due to various reasons, to-wit—some strands or line wires being longer than others, to the roll straightener on the fence machine doing other than taking most of the short kinks 30 and bends out the stay wires before the stay wire or wires enter the machine.

I have discovered, after a long practice in the actual manufacture of what we choose to call straight or stiff stay fencing and the use of same, that the flexing or bowing of the fence vertically, due to the reasons stated and many others which might be enumerated, is avoided by straightening the stay wires in the machine by and with the use of improved die-structures when applying the staple ties to the strand and stay wires. This is accomplished by providing the receiving and movable die members with complementary or coacting faces which crimp or impress indentations in the stay wires, at points adjacent to and on opposite sides of the line wires and applied staple tie wires, which takes up any slack or irregularities in the portions of the stay wires between the 45 respective sets of die members, and thereby

gives a better and more erect supporting effect of the several stay wires and a much better appearance to the fence fabric after it is stretched up. Furthermore, since it is a common practice, when applying the staple tie wires to the intersections of the strand and stay wires to apply the same by the movement of die sections from one side only of the strand and stay wires, there is a bowing effect to the stays which results in a 60 bowing effect to the fabric thruout the width of the fabric and thereby the length of the stays, and to counteract such action I have discovered that, if while applying the staple ties the die sections are caused to kink or indent the stay wires, as above pointed out, that the stay wires are thereby straightened, or in other words, the bowing is counteracted by such kinking and indenting and the stays caused to assume an erect or upstanding position and results in the fabric assuming an unbowed and erect position when stretched.

That the invention may be more fully understood, reference is had to the accompanying drawings forming part of this description, illustrating a preferred embodiment of the invention, in which:—

Fig. 1 shows in plan, side elevation and end view, a receiving die;

Fig. 2 is a sectional detail, in plan, showing the stationary and movable die sections and with a strand and stay wire in position at the time of the application of the staple tie and the complementary or coacting means 85 on the die sections.

Fig. 3 is a plan view, on a small scale, showing two sets of die-structures attaching a stay to strand wires by means of staples and straightening the stay;

Fig. 4 is a detail in section, as the same would appear on the line 4—4, Fig. 3;

Fig. 5 is a view similar to Fig. 4, except that the movable die section is out of contact with the stationary die;

Fig. 6 is a face view of a section of a fence made upon a machine embodying my die-structure, and

Fig. 7 is an edge view of the fabric shown in Fig. 6.

Like characters of reference denote corresponding parts throughout the figures.

Inasmuch as the invention herein is directed to the die-structure and particularly to the complementary or coacting faces of the die sections by means of which the stay wires are straightened during and at the time the staple wires are applied to the intersections of the strand and stay wires, and inasmuch as the arrangement and operation of these dies and the staple forming and driving means are all disclosed in Patent No. 1,078,702 and on which patent reliance is placed for an understanding of these features, no stress will be laid on the same here and no effort will be made to describe other than those features of structure which bear directly on the straightening means for the stay wires.

20 The stationary and receiving die member is designated 1 and the coacting and movable die member is designated 2. It is understood that there is one set of these dies adapted for coaction with and at the junction of each stay wire with a strand wire, with the exception of the marginal or selvage wires, at which point the ends of the stay wires are usually wrapped or coiled about the marginal or selvage wires and in this 25 type of structure there is usually employed a plunger 3 or some suitable means, preferably movable in the die section 2 to force and clinch the staple tie about the intersection of the stay and strand wires.

30 35 The acting face of the member 1 is formed or provided with the transverse wire grooves or slots 4 and 5; the former to receive and provide a seat for the body of the stay wire A and the latter to receive and provide a seat for the body of the strand wire B. The 40 end of the wire grooves or slots 4 are beveled, as at 6, to enable the stays to slip easily into and out of such grooves or slots. Disposed on opposite sides of the wire groove or slot 45 5 and extending for a short distance and parallel with said groove or slot, are what is called semi-circular die seats 7 to receive the same about the wires to be secured, when the 50 plunger or punch acts on the arcuate end of the said staple tie, the latter for convenience designated C.

The movable die section 2 is provided in its acting face with wire grooves or slots 55 forming seats for the wires A and B, one of such grooves or slots designated 8 is best seen in Fig. 2, and the ends of such slots are beveled, as at 9, adapted to function as do the beveled ends 6 of the groove or slot 4. 60 While I have not shown the means of adjusting the die sections 1 and 2 in their relation to each other, as in the patent referred to, it is to be understood that such a provision would be made to take up any wear 65 due to use and also for the purpose of ad-

justing the dies to the work in the machine that proper straightening of the stay wires may be accomplished.

The improvement which I have made in the die structure, and which is best seen in Fig. 2, consists in providing in the acting face of the die section 1 and preferably in the groove or slot 4 thereof, the outwardly presented, or what may be termed the "ball" faces or rounded projections 10, one on either side of and next adjacent the die seats 7, which said "ball" faces or rounded projections, toward the outer ends of the grooves or slots 4, recede into such groove or slot 4 by the concave face 11 terminated at the beveled ends 6. In contradistinction to this, the acting face of the die section 2 is provided, preferably in the groove or slot 8, with concave depressions 12, which normally act opposite and are complementary to the "ball" faces or rounded projections 10 on the section 1. These faces terminate at their outer portions in bearing points 13 and at their inner portions in bearing points 14.

As will be observed from an examination of Fig. 2, when wires A and B are threaded into the machine and the staple wire C is placed ready for clinching about the intersection of wires A and B, the die section 2 moves toward and into coacting position with the die section 1, while at the same time or in timed relation therewith the plunger or punch 3 is moved forward, engaging the arcuate end of the staple and causes its ends to be directed into the die seats 7 and as a result directed about the stay wire, as shown. The action of stapling is from one side and toward the stay wire and to effectively staple tie the wires, the stay is kinked at the intersection with the strand, as at D. This ordinarily has a tendency to bow or flex the fabric in the direction of application of the tie wires and it is at or about this moment in the operation, that the complementary or coacting straightening means on the die sections act to straighten the stay by kinking or indenting the stay at points adjacent to and on opposite sides of the point of application of the staple ties and reversely to the kink or bend D in the stay wire. These kinks or indentations in the stay are designated E. The die sections 1 and 2 act in the following manner—as the section 2 moves to engaging position, the points of bearing of the acting face of the die sections are at points 10, 13 and 14 with the "ball" faces or rounded projections indenting the stay at E and partially forcing the same between the points 13 and 14 into the concave depressions 12. The concave faces 11 in the section 1 will allow a slight depressing of the stay therein, as occasion may require, and as the stays are released from the dies whatever spring there is in the stays permits of their normal straight positions and with a better and more effec-

tive supporting action than where the stays are bowed or flexed.

I am aware, as I have pointed out that kinking strand wires in fence fabric is old, but I am not aware, during many years of manufacturing wire fence that any one has ever kinked or indented stay wires for the purpose of straightening the same, especially in straight or stiff stay fencing where staple ties are employed to connect the intersections of the strand and stay wires, wherein the stays become bowed or flexed and as a result the fabric will not stretch straight, will not remain upright and gives a bad or unsightly appearance. While I have elected to straighten the stay wires in the die structure, as being the most convenient and an economical way of accomplishing such straightening it should be obvious that once such result is accomplished modified practices may be employed and yet come within the spirit and scope of my invention and I, therefore, do not want to be limited other than is expressed by the scope of the claims appended hereto.

What I claim is:—

1. In a machine for staple tying strand and stay wires of a wire fence, means for stapling the wires, and means for substantially simultaneously straightening the stay wires which are bowed or flexed during the stapling operation.

2. In a machine for staple tying strand and stay wires of a wire fence, dies for stapling, and means in the dies for straightening the stay wires which are bowed or flexed as a result of the stapling operation.

3. In a machine for staple tying strand and stay wires of a wire fence, dies for stapling comprising a stationary receiving die and a die member movable toward and away therefrom, and means in the dies for straightening the stay wires which are bowed or flexed as a result of the stapling operation.

4. In a wire fence machine, means to connect the intersections of strand wires and crossed stay wires where they intersect, and means to kink the stay wires on opposite sides of their points of connection with the strand wires for straightening such stay wires.

5. A die structure for staple connecting strand and stay wires comprising die sections adapted to receive the strand and stay wires therebetween, and complementary faces on said die sections arranged for kinking the stay wires on opposite sides and next adjacent their points of connection with the strand wires for straightening said stay wires.

6. A die-structure for staple connecting strand and stay wires of a wire fence comprising coacting die sections adapted to receive the strand and stay wires therebetween,

each section having grooves providing seats respectively for the said strand and stay wires and one such section having die seats to receive the staples, one such section provided with convex-like projections, one on either side of and next adjacent the said die seats and the other section provided with concave-like depressions which are complementary to the said convex-like projections on the other section, the said projections and depressions adapted to kink the stay wires on opposite sides and next adjacent their points of connection with the strand wires whereby to straighten said stay wires which have been bowed or flexed as a result of the stapling operation.
